DIAPHRAGM FOR ACOUSTIC INSTRUMENTS OR APPARATUS

Filed Dec. 9, 1922

FIG. 2.

FIG. 3.

Inventor:

Charles B. Lenthall

By
Seidenberg & Borat
Atty.

UNITED STATES PATENT OFFICE

CHARLES BERTRAM LENTHALL, OF SOUTHPORT, ENGLAND

DIAPHRAGM FOR ACOUSTIC INSTRUMENTS OR APPARATUS

Application filed December 9, 1922, Serial No. 605,818, and in Great Britain April 18, 1922.

This invention has reference to diaphragms for acoustic instruments or apparatus. The invention is more particularly applicable to the diaphragms of instruments or apparatus for the reproduction of sounds, such as e. g. the sound boxes of gramophones and phonographs, telephone receivers and the like, but it is also applicable to the diaphragms of instruments or apparatus for transmitting and recording sounds, such as e. g. telephone transmitters, gramophone and phonograph record producers, dictating machines, telephonic apparatus for the use of persons with impaired hearing, and so forth.

The object of the invention is to provide improvements in the diaphragms of acoustic instruments and apparatus whereby to ensure a more brilliant and faithful reproduction or transmission or record of the sounds than is obtained with known diaphragms.

According to this invention a diaphragm for an acoustic instrument is provided with a concentric groove or dishing whereby the central area of the diaphragm is, so to speak, given a tension or a stiffness which is found to give improved results.

In the accompanying drawings Fig. 1 is a section of a gramophone sound-box fitted with one form of the improved diaphragm, and Figs. 2 and 3 are, respectively, a face view or plan and a section of the diaphragm removed.

Referring to the drawings, 4 is the sound-box and 5 is the diaphragm which is mounted therein and clamped between two packing rings 6 as usual. 7 is the stylus bar pivotally mounted on the box 4 at 8 and connected with the centre of the diaphragm at 9.

The diaphragm 5 is formed with a substantially wide and substantially shallow circumferential groove or dishing 10, the cross sectional arc of which is a segment of a circle, and the radial dimensions or width, or the chord of the curvature, of which is approximately one-third of the radius of the diaphragm.

The diaphragm is mounted in the sound-box 4 with the convexity of the groove or dishing 10 to the outside, though if desired

the concavity of the groove or dishing may be to the outside.

In gramophone sound boxes excellent results have been obtained with an aluminium diaphragm of one and fifteen sixteenths 55 inches diameter and .007 inch gauge, provided with a dishing or groove having a radius of one-quarter inch, a segmental angle of 105° and an outer diameter of one and three thirty-seconds inches, but I do not confine myself to these dimensions as same may be varied and still yield improved results. The outer diameter of the dishing or groove should not, however, exceed about two-thirds 60 of the diameter of the diaphragm, but the radius of the curvature of the dishing or groove may vary from approximately one-eighth to one-third of the diameter of the diaphragm and its segmental angle may vary from approximately 45° to 160°, the largest segmental angle being used with the smallest radius and vice versa. Alternatively, the width of the dishing or groove, or the chord of the curvature thereof, may vary between about one quarter and two-thirds of the radius 65 of the diaphragm.

The diaphragm may be made of other suitable materials than aluminium.

What I claim as my invention and desire to secure by Letters Patent is:—

1. For acoustic instruments or apparatus, a vibratory diaphragm provided with a single substantially wide and substantially concentric annular groove the cross sectional arc of which is a segment of a circle, and the radial chord of the curvature, of which is approximately one-third of the radius of the diaphragm.

2. For acoustic instruments or apparatus, a vibratory diaphragm provided with a concentric annular groove, the diameter of the outer edge of which does not exceed two-thirds of the diameter of the diaphragm, the cross sectional arc of which is a segment of 85 160° to 45° of a circle having a radius of 90 from one-eighth to one-third of the diameter of the diaphragm.

3. For acoustic instruments or apparatus, a vibratory diaphragm provided with a concentric annular groove the diameter of the 95 100

outer edge of which does not exceed two-thirds of the diameter of the diaphragm, the cross sectional arc of which is the segment of a circle, and the chord of the curvature, of
5 which is from one-quarter to two-thirds of the radius of the diaphragm.

In witness whereof I have hereunto set my hand.

CHARLES BERTRAM LENTHALL.
